UNITED STATES PATENT OFFICE.

RICHARD HENRY WHITEHEAD, OF NEW HAVEN, CONNECTICUT, ASSIGNOR TO NEW HAVEN CLOCK CO., OF NEW HAVEN, CONNECTICUT, A CORPORATION.

DESIGN FOR A CLOCK CASE.

Application filed September 26, 1923. Serial No. 7,329. Term of patent 14 years.

To all whom it may concern:

Be it known that I, RICHARD H. WHITEHEAD, a citizen of the United States, residing at New Haven, in the county of New Haven and State of Connecticut, have invented a new, original, and ornamental Design for a Clock Case, of which the following is a specification, reference being had to the accompanying drawing, forming part thereof.

I claim:

The ornamental design for a clock case as shown.

RICHARD HENRY WHITEHEAD.

Witnesses:

ROSE McKEON,
CATHERINE A. O'NEIL.
